PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA

OSCILLATION GENERATOR

Application filed July 15, 1927. Serial No. 205,924.

My invention relates to oscillation generators, and it has particular relation to generators of the thermionic-tube type designed to handle ultra-high frequencies.

5 The production and radiation of any considerable amount of power at ultra-high frequencies has heretofore been attended by numerous difficulties. The peculiarities of the various circuits used in connection with 10 the generation of oscillations at the usual frequencies employed in radio transmission are greatly emphasized when such circuits are given the reduced dimensions necessary for ultra-high frequencies, and, consequently, 15 unless many precautions are taken, the amount of power radiated may be vastly less than the predicted amount.

It has also been found extremely difficult to devise an ultra-high frequency oscillation 20 generator that is stable in operation. Numerous factors, such as varying electron emission from the tube filament, the influence of various stray capacities, physical changes in the circuit elements, etc., have 25 all contributed toward causing the oscillation-frequency to vary from instant to instant, and have heretofore very seriously interfered with the production of oscillations at wave-lengths of the order of fractions of 30 a meter.

It is, accordingly, an object of my invention to provide an ultra-high-frequency oscillation generator that is stable in operation.

35 Another object of my invention is to provide an ultra-high-frequency oscillation generator that is capable of a much higher power output than the generators known to the prior art.

40 Another object of my invention is to provide an ultra-high-frequency oscillation generator that is capable of radiating energy directly, without the necessity of employing a specific radiating structure analogous to 45 a loop or antenna.

Another object of my invention is to provide, in a generating system of the type described, means for isolating portions thereof subject to high frequencies from other 50 portions thereof without introducing losses.

In order to accomplish the above objects, I have found it advisable to utilize a specially designed thermionic tube in which the connection to the plate extends through the glass envelope at a point opposite to the points through which the grid and filament extend. In addition, I eliminate the necessity for employing radio-frequency choke-coils in certain of the power supply leads, by substituting therefor plain conductors 55 having a length which is a definite fraction of the wave length of the frequency of the oscillations generated.

I provide also a stabilizing oscillatory-circuit having a natural period comparable to the frequency of the oscillations generated. The stabilizing circuit enables me to generate 60 oscillations at wave lengths much shorter than those heretofore employed, and to obtain power outputs much greater than those 65 obtainable with circuits known to the prior art.

Among the novel features of my invention, are those particularly set forth in the appended claims. The invention itself, however, both as to its organization and its method of operation, together with further objects and advantages thereof, will best be understood from a consideration of the following description of certain specific embodiments, taken in connection with the accompanying drawings, in which:

Figure 1 is a view, partly diagrammatic and partly structural, illustrating a complete oscillation generating system arranged according to a preferred form of my invention, and

Fig. 2 is a diagrammatic view of a modified form of my invention, wherein the thermionic device itself is embodied in the radiating structure.

Referring specifically to Fig. 1, a thermionic device 1 having a plate 2, a filament 3 and a grid 4 is suspended by means of silk cords 5 and 6, or other insulating devices, 95 from a horizontally extending supporting bar 7 which, in turn, is carried by a stand 8.

The plate 2 is provided with input conductors 10 which extend through one end of the glass envelope. The filament 3 is pro- 100

vided with two conductors 11 and 12 which extend through the end of the glass envelope at a point opposite to the point at which the plate conductor 10 extends therethrough. The grid comprises a helical conductor 13 wound on two supporting members 14 and 15 which, in turn, are carried by a plurality of lead-in conductors 16 and 17 which extend to the outside of the glass envelope and are there joined together.

10 An oscillatory circuit 18, comprising a single loop 20 of copper tubing and a fixed condenser 21 constituted by plates 22 and 23 soldered to the ends of the tubing, its connected to the plate of the thermionic device through a stopping condenser 24 and to the grid of the device through a conductor 25.

The filament is supplied with energy from a source 26 through leads 27 and 28 which are one-quarter wave length long, the points at which these leads are connected to the source 26 being grounded through condensers 30 and 31. The positive pole of a C-battery 32 is connected to the midpoint of the filament-voltage source 26, and the negative pole thereof is preferably connected, by a conductor 33, to the physical center of the oscillatory circuit 18.

20 A source 34 of direct current is provided, the negative pole of which is connected to the midpoint of the filament-supply battery 26 by means of a conductor 35, and the positive pole of which is connected to the plate of the thermionic device by means of a conductor 36. The conductor 36 is connected to ground through a condenser 37, the length of the conductor 36 between the condenser and the plate lead-in conductor 10 being one-quarter of a wave length of the oscillations 40 to be generated.

The negative pole of the direct-current source 34 is grounded through a condenser 38, and the negative pole of the C-battery is grounded through a condenser 39.

45 The frequency generated by a system arranged according to Fig. 1, depends principally upon the capacity between the plate and the grid of the thermionic device, upon the length of the electrode supports in the interior of the tube, and also upon the length of an exterior connection between the grid and anode, which connection is necessary in order to include the blocking condenser 24 if the auxiliary stabilizing circuit 18 is not 50 present. A circuit of this general character is shown in Fig. 2, in which figure the blocking condenser 24 referred to is represented by dotted lines.

When the stabilizing circuit, including the 60 single-turn inductor 20 and the fixed condenser 21, is coupled to the thermionic device, as shown, it is necessary that the fixed condenser shall have a capacity of the same order of magnitude as the grid-plate capacity of 65 the tube. The single-turn inductor, there-

fore, must possess an inductance practically equal to the distributed inductance of the lead-in conductors associated with the tube and the inductance of the conductors necessary to associate the blocking condenser 70 therewith.

The system, as shown, therefore, comprises two coupled oscillatory circuits having substantially the same natural period. The thermionic device, by reason of its physical dimensions, tends to oscillate at a definite frequency, and the stabilizing circuit also tends to oscillate at this same frequency. As a consequence, the generation of oscillations is greatly stabilized by the presence of the auxiliary circuit, which circuit in no way militates against the generation of oscillations at as high frequencies as the characteristics of the thermionic device will permit.

25 The potential of the midpoint of the stabilizing circuit is fixed by its connection to ground through the condenser 39, which is preferably of large capacity. This point is, therefore, a voltage node or a point which is maintained at substantially zero voltage, 80 insofar as radio-frequency oscillations are concerned. The plates 22 and 23, constituting the fixed condenser in the auxiliary circuit 18, are analogous to voltage loops. The terms "voltage nodes" and "voltage loops", 85 while not strictly correct, insofar as conditions in my improved oscillation generating system are concerned, are believed sufficiently accurate to characterize those points therein which are subject to but little high-frequency-potential variation and those subject to maximum high-frequency-potential variation, respectively.

90 In one actual embodiment of my invention, the leads 36, 27 and 28 were 50 centimeters long and the over-all length of the tube itself was 17.78 centimeters, approximately. The capacity of the blocking condenser was 15 micromicrofarads, the capacity between the grid and plate of the tube was about 5 micromicrofarads, while the capacity of the fixed condenser in the auxiliary circuit was also about 5 micro-microfarads. The system oscillated very 95 steadily at a wave length of approximately two meters, and the power radiated was substantially 30 watts with 2200 volts applied to the plate of the tube.

100 At such high frequency, it is highly probable that neither the circuit comprising the tube elements nor the auxiliary circuit comprising the single-turn inductor and the fixed condenser oscillates as does the ordinary and well known tuned-circuit. I have not definitely established the exact mode in which 110 oscillations take place, though it appears highly probable that phenomena are present analogous to those manifested when stationary waves are caused to exist on Lecher-wires. At any rate, the conductors leading 115

to the plate and filament have potential loops developed on them near the points where they extend through the opposite ends of the thermionic device.

5 It is customary to interpose radio-frequency choke coils between the various sources of supply and the tube elements, in order that energy at radio frequency, shall not be by-passed through the said sources. 10 Such choke-coils, of necessity, consume an appreciable amount of energy, and consequently lower the efficiency of a system designed to generate oscillations at ultra-high frequencies. I have, accordingly, replaced 15 the aforesaid radio-frequency choke coils by plain conductors, each of which is one quarter of a wave-length long. I have further fixed the potential of the points at which these conductors are attached to the 20 voltage sources by grounding the said points through condensers having large capacity. The conditions precedent to the establishing of standing waves on these conductors are, therefore, present. The ends thereof nearest 25 the tubes are at what might be termed voltage loops, and the opposite ends are equivalent to voltage nodes. When in operation, therefore, no energy at radio frequency is transferred from either the filament or the 30 plate to the voltage sources associated therewith, and the efficiency of the system is materially increased. It is largely to the use of such quarter wave-length leads that I attribute my success in being able to cause 35 the radiation of an amount of power at ultra-high frequencies much greater than is possible with systems known to the prior art.

The auxiliary circuit 18 may be dispensed with in the event that it is not desirable to 40 radiate any large amount of power. A thermionic device may be substituted for the spark gap in the well known Hertz oscillator, in which case, the said device forms a part of the radiating structure, per se. A 45 system so arranged is illustrated in Fig. 2.

Referring specifically to Fig. 2, a thermionic device 50, having a filament 51, a grid 52 and a plate 53, is supplied with plate-potential from a source 54 through a 50 quarter-wave-length conductor 55 and with filament power from a source 56 through quarter-wave-length conductors 57 and 58. A C-battery 60, connected in series with a resistor 61, fixes the potential of the grid 55 with respect to the filament, or the C-battery may, if desirable, be omitted. I have not shown the grid-leak resistor 61 as being interposed in a quarter-wave-length conductor, inasmuch as, in an actual physical embodiment of this modification of my invention, the grid and filament lead-in wires would be quite close together.

A plurality of fixed condensers 62, 63, 64 and 65 of large capacity are interposed between the poles of the potential sources 54,

56, 60 and ground, and, therefore, fix the potential of the lower ends of the quarter wave-length conductors 55, 57 and 58.

A straight conductor 66 is affixed to the lead extending from the plate 53 of the thermionic device, and a similar conductor 67 is affixed to the grid lead. There is a definite amount of distributed capacity between these extensions of the plate and grid conductors which is represented by a condenser 68 shown in dotted lines.

The system illustrated in Fig. 2, when energized, tends to oscillate at a frequency determined by the over-all distance between the ends of the conductors 66 and 67, the stray capacity existing between them, and the capacity between the grid and the plate of the tube, unless the latter is very large. This frequency will be found to correspond, in general, to a wave length which is equal to the said over-all distance, the equivalence being modified by the inter-electrode capacity. Such a condition follows from the fact that the free ends of the conductors 66 and 67 are, of necessity, potential loops and from the fact that a potential loop exists on the grid and plate. The presence of these three potential loops indicates that the shortest wave which can be generated is one having a wave length corresponding to the said over-all distance.

The system illustrated in Fig. 2, is perhaps, a more efficient radiator than the system shown in Fig. 1. It is principally of value in connection with portable transmitters designed to cover short distances, since it obviates the necessity for supplying an additional radiating structure of any description.

A system constructed according to my invention, as illustrated in Fig. 1, is principally advantageous in that it permits a larger proportion of the power input to be effectively radiated in the form of ultra-high frequency oscillations than analogous systems known to the prior art. The oscillations produced are remarkably steady in amplitude and the frequency variation has been found to be much smaller than when the stabilizing circuit is not used. In this latter respect, my improved system is much superior to anything with which I have heretofore been acquainted.

Although I have shown and described only a few specific embodiments of my invention, many modifications and adaptations thereof will be apparent to those skilled in the art. My invention, therefore, is not to be limited except insofar as is necessitated by the prior art and by the spirit of the appended claims.

I claim as my invention:

1. Electrical apparatus including a thermionic tube connected by suitable circuit networks to sources of potential and arranged to generate high-frequency oscillations of a

definite wave-length, characterized in that the length of the connection between at least one of the elements of said tube and one of said sources is substantially one-quarter of 5 said wave-length.

2. Electrical apparatus including a thermionic tube connected by suitable circuit networks to sources of potential and arranged to generate high-frequency oscillations of a definite 10 wave length, characterized in that the length of the connections between a plurality of the elements of said tube and said sources are each substantially one-quarter of said wave-length.

15 3. In an oscillation generator arranged to generate oscillations of a definite wave length, a thermionic device comprising an anode, a source of potential for said anode, and a connection between said source and 20 said anode of a length substantially equal to one-quarter of the wave-length of the oscillations generated.

4. In an oscillation generator arranged to generate oscillations of a definite wave length, a thermionic device comprising a cathode, a source of potential for energizing said cathode, and connections between said source and said cathode of a length substantially equal to one quarter of the wave-length 30 of the oscillations generated.

5. In an oscillation generator, a thermionic device having a plurality of electrodes, an oscillating circuit having a frequency determined by the capacity between certain of said 35 electrodes and materially influenced by the length of the leads extending from said electrodes to the exterior of said thermionic device, a second stabilizing circuit comprising an inductor and a condenser of the order of 40 the inter-electrode capacity, and connections between said second circuit and certain of the said electrodes.

6. In an oscillation generating system, a thermionic device having a cathode, an anode, and a control electrode, an oscillatory circuit including a stopping condenser and the inter-electrode capacity between said anode and said control electrode, the period of 45 said circuit being determined by the said inter-electrode capacity and by the length of the connections whereby said stopping condenser is included in circuit, and a stabilizing circuit coupled to said oscillatory circuit, said stabilizing circuit including a condenser of the order of magnitude of said 50 inter-electrode capacity and having a period substantially equal to the period of said oscillatory circuit.

In testimony whereof, I have hereunto 60 subscribed my name this 30th day of June, 1927.
PHILLIPS THOMAS.
